UNITED STATES PATENT OFFICE.

JOSEPH R. BLAINE, OF CHICAGO, ILLINOIS, ASSIGNOR TO MIEHLE PRINTING PRESS & MANUFACTURING CO., OF CHICAGO, ILLINOIS, A CORPORATION OF ILLINOIS.

FORM-ROLL TRIP MECHANISM.

Application filed March 28, 1921. Serial No. 456,260.

To all whom it may concern:

Be it known that I, JOSEPH R. BLAINE, a citizen of the United States, residing at Chicago, in the county of Cook and State of Illinois, have invented certain new and useful Improvements in Form-Roll Trip Mechanism, of which the following is a specification.

This invention relates to form roll trip mechanism, and is an improvement of the same type of mechanism disclosed in my copending application, Serial No. 92,819, filed April 22, 1916.

The object of this invention is to simplify and improve the construction and operation of form roll trip mechanism in a manner to meet the various requirements for successful commercial operation.

The invention is illustrated on the accompanying sheets of drawings, in which—

Figure 1 is a fragmentary side elevation of an offset press showing my improved form roll trip mechanism;

Figure 2 is a fragmentary enlarged side elevation of said trip mechanism; and,

Figure 3 is a fragmentary side elevation showing the various rolls associated with the form cylinder in their cooperative positions.

In view of the fact that many parts of this form roll trip mechanism are disclosed in my said copending application, only such parts which form the present invention will be specifically described, some of the other parts being referred to only in a general way.

As is well understood in the art, inking rolls are tripped to prevent too much ink being supplied to the plate cylinder when no sheets are fed through the press, or, in other words, the inking rolls are tripped under certain conditions to maintain a uniform supply of ink on the plate cylinder. Furthermore, it is necessary, in order to prevent bad marking or uneven inking, to have the rolls tripped on and off at the gap in the cylinder, and in this particular case the rolls are tripped on and off sequentially because the rolls cover a space larger than the gap. With the present mechanism, as also with the mechanism in my copending application, the inking rolls are tripped on and off, fully automatically, and also optionally by hand.

Referring to the figures of the drawings, it will be noted that I have shown a form

cylinder 10, cooperating with which are two sets 11 of inking rolls, each including three inking rolls 12 which under normal printing conditions engage the plate cylinder 10 for distributing ink thereon. Four pivotally mounted frame members 13 are provided, two at each end of the rollers, and accordingly only two are shown in the figures of the drawings. Each of the frame members is pivotally mounted, as at 14, and has projecting portions 15, 16 and 17 engaged by portions of the inking rolls 12, the last two projections in each case being more pronounced. The inking rolls normally rest upon the plate cylinder 10, but just clear the projections of the plate members 13, and accordingly, if the plate members 13 are caused to rise and fall about their pivotal points 14, the inking rolls likewise will rise out of engagement or fall into engagement with respect to the plate cylinder 10.

To control the rise and fall of the rolls, I have provided the frame members 13 with cam slots 18, which are traversed by projections 19 in each case carried at the end of one arm 20 of a bell crank lever pivoted at 21, the other arm of the bell crank lever being in the form of a toothed segment 22, which meshes with the teeth 23 of a composite rack trip bar 24, the teeth 25 on the opposite side of the bar 24 being in mesh with a segment 25' forming part of a bell crank lever 26 pivotally mounted at 27 and having another arm 28. From the arrangement thus far described, it is apparent that if the rack trip bars 24 are forced downwardly, the segments 22 will be rocked downwardly and the projections 19 of arms 20 will be forced downwardly in the cam slots, which are eccentrically arranged with respect to the pivotal centers 21 of the bell crank levers, causing the frame members 13 to swing upwardly about their pivotal centers 14 for raising the inking rolls and disengaging the latter from the form cylinder 10. Likewise, when the trip bars 24 are permitted to spring back into normal position as a result of energy stored in return springs 29, the arm projections 19 will move upwardly in the eccentric cam slots 18 to permit the inking rolls 12 to move back into engagement with the form cylinder 10. As stated hereinabove, in view of the fact that the inking rolls 12 cover a space wider than the gap, these rolls in sets are raised and

lowered in a given sequence, the action being entirely automatic, as disclosed in my said copending application.

For manually raising and lowering the inking rolls 12, a lever 26 is pivotally connected by a link 30 to one arm 31 of a control lever 32 pivoted at 33. The lever 26 on the oppositely arranged lever 28 is pivotally connected by a link 34 to another arm 35 of said lever 32 having a handle portion 36.

In the figures of the drawings the inking rolls 12 are in engagement with the form cylinder 10, and, as shown in dotted lines in Figure 2, the inking rolls are tripped out of engagement with said form cylinder. This tripping action may be automatic, or manual, as hereinabove described. By means of this simple and improved form roll trip mechanism, including the frame members having eccentrically formed cam slots, the efficiency and operation of the trip mechanism is made more commercial.

It is my intention to cover all modifications of the invention falling within the spirit and scope of the following claim.

I claim:

In combination, a form cylinder, a pair of sets of inking rollers cooperating therewith, a pair of sets of frame members, each of said sets of frame members including two frame members mounted at the ends of said rollers, each of said frame members having projecting members engaging portions of said rollers, said frame members having cam slots, arms for operating said frame members, said arms being provided with projections adapted to ride in said cam slots, and rack trip bars for operating said arms, said bars having means for manually operating same.

Signed at Chicago, Illinois, this 25th day of March, 1921.

JOSEPH R. BLAINE.
